United States Patent

Des. 241,399
Patented Sept. 14, 1976

241,399

COVERED FOOD DISH

Hubert E. Christian, Phoenix, Ariz., assignor to Dart
Industries Inc., Los Angeles, Calif.

Filed Dec. 27, 1974, Ser. No. 536,757

Term of patent 14 years

Int. Cl. D7—01

U.S. CL. D7—17

FIG. 1

FIG. 2

FIG. 3

FIG. 4

FIG. 5

FIG. 1 is a top perspective view of a covered food dish showing my new design;

FIG. 2 is a side elevation view;

FIG. 3 is a top plan view;

FIG. 4 is a bottom plan view; and

FIG. 5 is a cross-sectional view on an enlarged scale taken along line 5—5 of FIG. 3.

I claim:

The ornamental design for a covered food dish, substantially as shown and described.
